UNITED STATES PATENT OFFICE.

HAROLD K. HUGHES, OF BROOKLYN, NEW YORK.

OIL-SEPARATOR.

1,131,243.

Specification of Letters Patent.

Patented Mar. 9, 1915.

Application filed November 3, 1914. Serial No. 870,000.

To all whom it may concern:

Be it known that I, HAROLD K. HUGHES, a citizen of the United States, and a resident of the borough of Brooklyn, county of 5 Kings, State of New York, have invented certain new and useful Improvements in Oil-Separators, of which the following is a specification.

The object of my invention is to provide 10 an effective, simple and convenient apparatus for separating oils from water, and also for removing the solids which may be present in the mixture.

The separator is designed more particu- 15 larly for installation in drainage systems leading from floors of buildings, to enable the removal and recovery of oils which would otherwise accumulate on the premises but which, mixed with water and more or 20 less solid matter, may be carried off by suitable drains to the separator.

In the accompanying drawings illustrating the invention: Figure 1 is a front elevation of the separator without the access 25 well; Fig. 2 is a plan view showing the separator with the access well, the cover of the latter being partly broken away; and Fig. 3 is a side view of the separator, with a portion of the access well.

30 The separator comprises a primary separating or inlet chamber 2 and a secondary or main separating chamber 3, preferably consisting of smaller and larger metal tanks secured side by side. The inlet 4 from the 35 floor drains delivers substantially horizontally into the upper and front part of the primary chamber, the arrangement being such that the influent impinges against the solid portion of the wall 5 separating the 40 chambers, thus causing the influent to throw down its solids of a greater specific gravity than water. The lower part of the chamber 2 constitutes a sedimentation basin, having a bottom 6 sloping to a discharge 7 controlled by a quick-operating valve 8.

The two chambers are connected in series, the communication between them being at their upper portions and at a region laterally removed from the inlet 4. To this 50 end the wall 5 is provided with a perforated area 9 in its upper and rear portion. These openings retain floating solids, while permitting the oil and water to pass to the secondary chamber, and their total area 55 should be greater than the area of the drain connection. They are confined to the up-

per portion of the wall, in order to prevent sediment being carried into the secondary chamber, yet extend downward a sufficient distance to avoid losing the benefit of the 60 partial separation of water and oil which takes place in the inlet chamber. Being laterally removed from the inlet they afford sufficient opportunity to the liquid to deposit its heavy solids before reaching the 65 main chamber.

An uptake water outlet pipe 10 leads from the lower part of the main chamber and terminates in a down-flow pipe 11 leading to the sewer, the point of overflow being 70 designated 30, and being located at such height as to maintain substantially the same level in both chambers and to cause the inlet 4 to deliver the influent into the primary chamber substantially without fall. As 75 shown, the overflow is above the bottom level of the area of communication 9 and slightly below the center line of the inlet, and it will be understood that the specific 80 distances giving best results can be ascertained by test in any particular case. Manifestly the arrangement of the water outlet prevents escape therethrough of the oil, which is drawn off from time to time through a stop-cock 12 at the front and upper 85 section of the drain tank, near the line of demarcation of the oil and water. The lower end of the pipe 10 preferably connects with the tank by a T 13, which has a removable cap 14 for cleaning. The fitting 90 15 connecting the pipes 10 and 11 at the top likewise has a removable cap 16, and this may fit somewhat loosely if desired, in order to insure against siphoning, though the size of the pipe 11 in relation to the quantity 95 of flow is sufficient to prevent such action.

The chambers are provided with covers 17 and 18, and a vent pipe 19 extends from an opening in the cover 18 of chamber 3 100 upward to a suitable elevation. In order to facilitate access when the installation is underground, a shell 20 is provided extending forward from the tanks, to the remote sides of which it is secured, in order to constitute an access well, where the valve 8, cock 12, etc. may be reached. This well is closed at the top by a cover 21 resting on lugs 22 and 23 on the shell and tank and having handles 24 by which it may be removed. 105

In operation the influent is delivered

from the inlet against the wall 4, its velocity is checked and its course diverted, with the result of causing it to deposit its heavy solids. The latter may be discharged as often as may be necessary by opening the valve 8, a suitable vessel being placed beneath the elevated bottom of this chamber to receive the sediment, and the quick opening and closing valve enabling the operation to be performed with certainty. A partial separation of the oil and water also takes place in the primary chamber, and is completed in the secondary chamber, where all the oils lighter than water rise and float on the surface, where they are drawn off as required, the water being allowed to escape in the manner already described.

What is claimed as new is:

1. An oil separator comprising separating chambers communicating in series, means for admitting the mixture to be separated to one of said chambers, an uptake water outlet connected with the lower part of the second chamber, means for drawing off oil from the upper part of the second chamber, a sedimentation basin at the bottom of the admission chamber, and means distinct from the water outlet for discharging accumulations from said basin.
2. An oil separator comprising separating chambers having means of communication between their upper portions, an inlet for admitting the mixture to be separated to one of said chambers, the said chamber having a sedimentation basin at its bottom, means for discharging accumulations therefrom, an uptake water outlet connected with the second chamber only and terminating in an overflow above the bottom level of the communication between the chambers, and means for drawing off oil from the top of said second chamber.
3. An oil separator comprising an inclosure having an inlet for the mixture to be separated, an uptake water outlet terminating in an overflow disposed at such height that the influent enters the inclosure from said inlet substantially without fall, a wall opposed to said inlet to cause the influent to throw down solid matter, a sedimentation basin below said wall and inlet, means distinct from the water outlet for discharging accumulations from the bottom of said basin, and means for drawing off oil from the upper part of the inclosure.
4. An oil separator comprising a main separating chamber, an inlet chamber alongside said main chamber and having a sedimentation basin at its bottom, an inlet delivering substantially horizontally into the upper part of the inlet chamber, means opposed to said inlet to cause the influent to throw down solid matter, an outlet from the upper part of the inlet chamber to the main chamber at a region laterally removed from
5. An oil separator comprising a primary separating chamber, an inlet for admitting the mixture thereto, means for collecting solids of greater specific gravity than water in the lower part of said chamber and discharging the accumulations therefrom from time to time, a secondary separating chamber in communication with the upper part of the primary chamber, means for retaining solids of less specific gravity than water in said primary chamber, an uptake water outlet connected with the lower part of said secondary chamber only, and means for drawing off oil from the upper part thereof.
6. An oil separator, comprising primary and secondary chambers having a wall therebetween, an inlet arranged to deliver the influent into the primary chamber toward the secondary chamber against said wall, said wall having an opening connecting the upper parts of the chambers at a region laterally removed from said inlet, an uptake water outlet from the lower part of the secondary chamber, means for drawing off oil from the upper part thereof, and means distinct from the water outlet for discharging accumulations of solids from the bottom of the primary chamber.
7. An oil separator, comprising primary and secondary chambers having a wall therebetween, an inlet arranged to deliver the influent into the primary chamber toward the secondary chamber against said wall, said wall being for the most part solid but having a perforated area in its upper portion laterally removed from the inlet, a sedimentation basin at the bottom of the primary chamber, means for discharging accumulations from time to time from said basin, an uptake water outlet from the lower part of the secondary chamber, and means for drawing off oil from the upper part thereof.
8. An oil separator comprising a main tank, an inlet chamber alongside the main tank and having a bottom above the bottom of the main tank and sloping to a discharge, a quick-operating valve controlling said discharge, an inlet opening into the upper part of the inlet chamber, means of communication between the upper parts of the chambers, an uptake water outlet connected with the lower part of the main tank only, and means for drawing off oil from the upper part thereof.
9. An oil separator comprising a main separating chamber, an inlet chamber alongside the main chamber and having means of communication therewith, a sedimentation basin at the bottom of said inlet chamber,

said inlet, an uptake water outlet from the lower part of the main chamber, means for drawing off oil from the upper part of said main chamber, and means distinct from the water outlet for discharging accumulations from the bottom of the sedimentation basin.

70

5. An oil separator comprising a primary separating chamber, an inlet for admitting the mixture thereto, means for collecting solids of greater specific gravity than water in the lower part of said chamber and discharging the accumulations therefrom from time to time, a secondary separating chamber in communication with the upper part of the primary chamber, means for retaining solids of less specific gravity than water in said primary chamber, an uptake water outlet connected with the lower part of said secondary chamber only, and means for drawing off oil from the upper part thereof.

80

6. An oil separator, comprising primary and secondary chambers having a wall therebetween, an inlet arranged to deliver the influent into the primary chamber toward the secondary chamber against said wall, said wall having an opening connecting the upper parts of the chambers at a region laterally removed from said inlet, an uptake water outlet from the lower part of the secondary chamber, means for drawing off oil from the upper part thereof, and means distinct from the water outlet for discharging accumulations of solids from the bottom of the primary chamber.

90

7. An oil separator, comprising primary and secondary chambers having a wall therebetween, an inlet arranged to deliver the influent into the primary chamber toward the secondary chamber against said wall, said wall being for the most part solid but having a perforated area in its upper portion laterally removed from the inlet, a sedimentation basin at the bottom of the primary chamber, means for discharging accumulations from time to time from said basin, an uptake water outlet from the lower part of the secondary chamber, and means for drawing off oil from the upper part thereof.

100

8. An oil separator comprising a main tank, an inlet chamber alongside the main tank and having a bottom above the bottom of the main tank and sloping to a discharge, a quick-operating valve controlling said discharge, an inlet opening into the upper part of the inlet chamber, means of communication between the upper parts of the chambers, an uptake water outlet connected with the lower part of the main tank only, and means for drawing off oil from the upper part thereof.

110

9. An oil separator comprising a main separating chamber, an inlet chamber alongside the main chamber and having means of communication therewith, a sedimentation basin at the bottom of said inlet chamber,

120

125

130

means for discharging accumulations from said basin from time to time, an uptake water outlet from the lower part of said main chamber, and means for drawing off oil 5 from the upper part thereof, in combination with a shell extending from said chambers at one side and affording an access well.

In witness whereof, I have hereunto set my hand this second day of November, one thousand nine hundred and fourteen.

HAROLD K. HUGHES.
